Inventor:

Wallace B. Sutherland
By Wm. J. Bell, Agt.

UNITED STATES PATENT OFFICE

WALLACE B. SUTHERLAND, OF SUFFERN, NEW YORK, ASSIGNOR TO THE AMERICAN BRAKE SHOE AND FOUNDRY COMPANY, OF WILMINGTON, DELAWARE, A CORPORATION OF DELAWARE

BRAKE SHOE

Application filed May 9, 1931. Serial No. 536,147.

This invention relates to brake shoes and more particularly to those cast iron shoes which are provided with reenforce backs and which may or may not be provided with inserts in the wearing face.

One of the objects of the invention is to rigidly unite the cast iron body and the reenforce back.

Another object of the invention is to provide a reenforce back having portions thereof bent downwardly in a novel manner into the cast iron body and forming a locking engagement therewith to prevent parts of the body falling away from the shoe in the event of its fracture.

I have shown the invention in a car shoe having a ductile metal back commonly called a steel back and with a solid cast iron body, and referring thereto

20 Fig. 1 is a side elevation showing the back in full lines and the bent down portions of the back in broken lines.

Fig. 2 is a top plan view of Fig. 1.

25 Fig. 3 is a sectional view on the line 3—3 of Fig. 1.

Fig. 4 is a sectional view on the line 4—4 of Fig. 1.

30 Fig. 5 is a sectional view showing a modified form of the invention.

Referring to the drawing, 6 is the body of the shoe, 7 is the ductile metal back, and 8 is the attaching lug. The back is in channel form having its marginal side edge portions bent downwardly to form flanges 9

35 which enclose the adjacent corners of the body. At each side of the longitudinal center of the back it is provided with a plurality of downwardly inclined and transversely extending tongues or sections 10,

40 Figs. 1—4, which are embedded in the body. These tongues or sections are formed by cutting the back and bending the tongues or sections downward, and enlarged openings 11 are formed in the back at the tongues to

45 receive the body metal in the casting operation. In Figs. 1—4 the tongues project downwardly and outwardly from the longitudinal middle portion of the back towards the flanges 9 and in Fig. 5 the tongues 12

50 project downwardly and inwardly from the

flanges 9 towards the longitudinal middle of the shoe. The cast iron fills the openings 11 and makes interlocking engagement with the tongues to securely unite the body and back. In Figs. 1—4 the body metal is buttoned, in effect, between the tongues and the flanges, and in Fig. 5 the body metal is buttoned, in effect, between opposing tongues and between the tongues and the inner edges of the openings. The ends of the back have 66 projections 13 with dovetail recesses 14 therebetween. These projections are bent upwardly and are completely embedded in the end lugs 15. The cast iron fills the dovetail recesses and makes interlocking engagement between the projections and lugs to securely unite the ends of the back and the body at the end lugs thereon. The back is also provided with elongated openings 16 at or about its middle and adjacent each 70 side thereof to receive the body metal which flows through said openings to form the reinforcing projections 17 of the attaching lug.

The invention provides a simple and efficient means for securely uniting the body and back of a brake shoe so that in event of the body fracturing in use the parts thereof will be retained on the back to continue to give braking service and will be 80 prevented from falling away and possibly causing damage and injury.

I do not restrict the invention to the particular embodiment illustrated in the drawing but propose to employ it in any shoe 85 for which it is or may be adapted and I reserve the right to make all changes in the form, construction and arrangement of parts within the scope of the following claims.

I claim:

1. A brake shoe comprising a body, a back on the body and having side edge flanges enclosing corners of the body, downwardly inclined and transversely extending tongues 95 on the back adjacent said flanges and embedded in the body, and lugs on the body, and upturned projections with dovetail recesses therebetween embedded in the end lugs.

2. A brake shoe comprising a one-piece 100

- reenforce back and a body cast thereon, side edge flanges on the back enclosing the adjacent corners of the body, and downwardly and transversely extending tongues stamped from the back, said back having openings formed by stamping said tongues and said openings being enlarged opposite the tongues to permit the body metal to flow freely into the openings during the casting operation for securing the body to the back.
3. A brake shoe comprising a one-piece reenforce back and a body cast thereon, side edge flanges on the back enclosing the adjacent corners of the body, and downwardly and inwardly extending tongues stamped from the back at the top of said flanges, said back having openings formed by stamping said tongues and said openings being enlarged transversely of the back to permit the body metal to flow freely into the openings during the casting operation for securing the body to the back.
4. A brake shoe comprising a one-piece reenforce back and a body cast thereon, side edge flanges on the back enclosing the adjacent corners of the body, and downwardly and transversely extending tongues stamped from the back, said back having openings formed by stamping said tongues and said openings being enlarged opposite the tongues to permit the body metal to flow freely into the openings during the casting operation for securing the body to the back, an attaching lug, and said back having elongated openings between the side flanges to permit the body metal to flow therethrough during the casting operation and form reinforcements for the attaching lug.

WALLACE B. SUTHERLAND.
